United States Patent Office

Des. 216,386
Patented Dec. 30, 1969

216,386

NECK UNIT FOR A COLLAPSIBLE TUBE

William T. Suggs, West Orange, N.J., assignor to Dart
Industries Inc., a corporation of Delaware

Filed Apr. 28, 1967, Ser. No. 6,873

Term of patent 14 years

Int. Cl. D9—99

U.S. Cl. D9—253

FIG. 1

FIG. 2

FIG. 3

FIG. 1 is a side view of a neck unit for a collapsible tube, showing my new design;

FIG. 2 is a top plan view thereof;

FIG. 3 is a bottom plan view thereof; and

FIG. 4 is a view similar to FIG. 1 with the lefthand portion in cross-section.

I claim:

The ornamental design for a neck unit for a collapsible tube, as shown.
